UNITED STATES PATENT OFFICE.

MARIO FERNANDEZ ARIAS, OF NEWARK, NEW JERSEY.

CUSHION SEAT.

Application filed December 11, 1923. Serial No. 679,992.

To all whom it may concern:

Be it known that I, MARIO FERNANDEZ ARIAS, a subject of the King of Spain, and a resident of Newark, in the county of Essex and State of New Jersey, United States of America, have invented a new and Improved Cushion Seat, of which the following is a full, clear, and exact description.

This invention has relation to seats for chairs, stools or the like and primarily aims to provide a seat which will give the desired cushioning effect without bulkiness.

As a further object the invention contemplates a cushion seat which is provided on its under surface with means for defining a plurality of air pockets when applied to the chair or stool which function to enhance the cushioning effect of the seat, prevent casual displacement of the seat from the chair bottom, while at the same time allowing for a sufficient amount of play or movement in the seat to prevent friction between the same and the clothing of the user.

As a still further object the invention contemplates a cushion seat of the character set forth which is extremely simple in its construction, inexpensive to manufacture, and which is highly efficient in its purpose.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

40 In the drawings:—

Figure 1 is a top plan view of a cushion seat constructed in accordance with the invention.

Fig. 2 is a bottom plan view thereof.

45 Fig. 3 is a cross sectional view therethrough taken approximately on the line indicated at 3—3 in Fig. 1.

Fig. 4 is a top plan view of a modified form of the invention.

50 Fig. 5 is a bottom plan view thereof.

Fig. 6 is a fragmentary cross sectional view thereof taken approximately on the line 6—6 of Fig. 4.

55 Referring to the drawings by characters of reference, the cushion seat comprises a piece of material 10 which embodies the

characteristics of sponge rubber and which is formed on its under face with a plurality of endless ribs 11 preferably integral with the body 10 and paralleling the marginal edge of the same to define between said ribs a plurality of endless recesses 12, which, when the seat is arranged on the chair bottom, define closed air pockets for enhancing the cushion effect of the material from which it is constructed, and which further function to prevent casual displacement of the seat from the chair while allowing for a sufficient play or movement of the same to prevent rubbing or friction between the clothing of the user which would tend to produce a shine on the garment. Preferably the upper face of the body 10 is lined with a fabric 13.

In the modified adaptation of the invention illustrated in Figs. 4, 5 and 6 the body 75 10^a is of substantially circular formation and is formed with a plurality of concentric endless ribs 11^a on its under face which define a plurality of concentric recesses 12^a which further define air pockets on the stool 80 S when the cushion seat is applied thereto.

In this form it is found preferable to provide the marginal edge of the cushion seat with a depending contractile flange 14 which is adapted to embrace the edge of the 85 stool S for the purpose of retaining the cushion seat in place thereon and against displacement prior to the imposition of the weight of the user thereon. In this form the upper face of the cushion seat is lined or 90 covered with a fabric 13^a as in the preferred embodiment.

I claim:

1. A cushion seat comprising a body constructed of a material having the qualities of sponge rubber and formed with a plurality of endless ribs on its under face paralleling the margin of the body and defining together with the article upon which it is superimposed a plurality of closed air pockets for enhancing the cushioning effect of the material from which it is constructed and for preventing casual displacement of the same from said article when the weight of the user is imposed thereon. 100

2. A cushion seat comprising a body constructed of a material having the qualities of sponge rubber and formed with a plurality of integral endless ribs on its under face paralleling the margin of the body and defining together with the article upon which it is superimposed a plurality of 105 110

closed air pockets for enhancing the cushioning effect of the material from which it is constructed and for preventing casual displacement of the same from said article when the weight of the user is imposed thereon.

3. A cushion seat comprising a body constructed of a material having the qualities of sponge rubber and formed with a plurality of endless ribs on its under face paralleling the margin of the body and defining together with the article upon which it is

superimposed a plurality of closed air pockets for enhancing the cushioning effect of the material from which it is constructed and for preventing casual displacement of the same from said article when the weight of the user is imposed thereon, and a contractile marginal depending flange on said body for engaging the edge of a stool to assist in preventing displacement of the cushion seat therefrom prior to the imposition of the weight of a person thereon.

MARIO FERNANDEZ ARIAS.
